COIN SORTING TOY BANK

Francis Morse, Dalton, Mass.

Application December 13, 1954, Serial No. 474,924

1 Claim. (Cl. 133—3)

This invention relates to improvements in a coin sorting toy bank and has for one of its major objects, besides the recreation provided by all toys, to provide also scientific education to the user—young and old—by arousing his curiosity as to the mode of operation of the device and by stimulating his observation and analysis of its principles. For this latter purpose, the major parts of the device are made of a transparent plastic material.

Although in its simple and inexpensive form, intended for wide distribution and educational utility, the toy bank of the present invention is designed for only three kinds of coins, namely nickles, dimes and quarters, yet in the light of the explanations given below, its extension to a greater variety of coins in more expensive forms will be evident to those skilled in the art.

Fig. 1 is a perspective view of the bank, and Fig. 2 a partial cross section of it made by a plane passing through the line 2—2 of Fig. 1 and normal to the axis of operation of the device, while Fig. 3 is a section taken along the line 3—3 of Fig. 2 and showing a coin pocket in the principal coin-sorting member of the device. Figs. 4, 5, and 6 show in section the situations of various kinds of coins on their way to their respective destinations.

In all of the figures the same part is identified by the same numeral for ease of reference.

Referring now more particularly to Figs. 1 and 2 jointly, 8 is a coin to be deposited in bank 9 having a transparent shell 10, through which three coin bins 18, 20 and 22 may be seen at the bottom of the bank, with partitions 19 and 21. The shell 10 of the bank will be seen to be semi-cylindrical at the top and enclosing a rotatable drum pivoted at 12 and having a coin pocket 14. In the operative position of the bank shown in Figs. 1 and 2, the bank is ready to receive a coin, and this position is referred to hereafter as the "normal position" of the bank. In this position, the coin pocket 14 is aligned with slot 13 in the shell to permit the insertion of a coin 8 through the slot 13 into the coin pocket 14. This alignment is rendered positive by means of a counterweight 17 tending to rotate the drum counterclockwise (Fig. 2), and a pawl-like detent or stop member 15 engaging a ridge 16 on the drum (Fig. 2) at this exact position.

It may be observed in both figures (1 and 2) that in this normal position of the bank, the coin pocket points with its open end generally upward, though not vertical but sufficiently off the vertical to provide leverage enough for the lightest coin inserted in the coin pocket to cause the drum to rotate clockwise. In the course of this rotation, the drum carries the coin pocket downward and also rotates it, so that eventually the coin pocket is turned upside down to permit the coin to drop out into one of the three bins 18, 20 and 22, provided under the drum. How the three kinds of coins are selectively dispensed into their respective bins will be explained after some further structural details of the device involved in this process are described.

Inspection of Fig. 2 will reveal that in the coin pocket 14 there is a shallow recess 14a in the lower wall of the

2

pocket, forming a low step 14b near the open end of the pocket. The pocket 14 is large enough to accept a quarter dollar without letting it project out of the pocket; while the recess is just a little too small to take the quarter, though it is large enough to take a nickle, and of course a dime—one at a time. So when a quarter dollar is placed in the coin pocket, it rides over the step 14b as illustrated by the shaded sectional view of Fig. 6 where coin 8a will be seen as riding on the step 14b. A coin smaller than a quarter, however, will drop into recess 14a and get caught behind the wall of step 14a, as illustrated by the shaded sectional views of Figs. 4 and 5.

The operation of the bank to deliver a coin selectively to its appropriate bin will now be explained coin by coin.

Processing of the quarter dollar

When a quarter dollar 8a (Fig. 6) is inserted in the coin pocket in the normal position of the bank illustrated in Figs. 1 and 2, the drum rotates clockwise, and in about 20 a 60 degree rotation, the coin pocket has become approximately horizontal as illustrated by the shaded sectional view of Fig. 6. As the quarter rides on the step 14b and is unobstructed by it, when the coin pocket dips below the horizontal and slants downward, the coin begins to 25 slide out. By the time the coin pocket has gone far enough to be aligned with the partition 19 between the bins 18 and 20, a portion of the coin will be projecting out of the pocket, as illustrated by coin 8a, in the unshaded dot-and-dash view of Fig. 6 and will be arrested by this 30 partition, thereby becoming forced to drop into bin 18. When the coin is thus discharged and the drum is relieved from the pressure of the coin, the counterweight 17 returns the drum back to the normal—loading—position.

Processing of the dime

When a dime 8b (Fig. 5) is loaded into the coin pocket, it drops into the recess 14a. The drum rotates as before, but when the coin pocket is slanting downward, the dime, having been caught behind the step 14b, cannot slide out as the quarter does, so the drum, and with it the coin pocket, rotate farther, approaching the position in which the coin pocket is pointing directly downward. Even in this position the dime cannot just slide out smoothly, as illustrated by the shaded sectional view of Fig. 5. 45 However, in this position, the supporting of the coin by the shallow step 14b becomes very insecure and the coin may slip out of the step and fall out. If it does not, the rotation continues further, and the coin becomes still more insecure on the narrow step 14b; and by the time 50 the coin pocket reaches the partition 21, the dime has either fallen into the bin 20, as illustrated by the unshaded dot-and-dash view of Fig. 5, or else it is projecting out far enough to be arrested by this partition and forced to fall into the bin 20. The wall of step 14b should not 55 be higher than the thickness of the dime, and preferably less. The angle of the wall of the step also has a bearing on the ease or difficulty with which the dime will drop out in the zone assigned to it. If the plane of the wall of step 14b is so oriented that in the upside-down position 60 of the pocket it slants downward a little, the coin will slip out easier and therefore sooner.

As a penny has about the same dimensions and weight as the dime, compared with the nickle and the quarter, the step 14b is preferably adjusted to operate equally well 65 with either coin, so that the more affluent patrons of the bank may play banking with dimes, the less affluent ones with pennies.

Processing of the nickel

Being substantially smaller than the quarter, the nickel 70 also drops into the recess 14a, just as the dime, and is rotated to the upside-down position without dropping out. So far as being supported by the step 14b is con-

cerned, the nickel is a little more insecure than the dime, but now another factor carries the nickel beyond partition 21 into bin 22 without mishap, as follows.

Since in their rotation from the loading position to the upside-down position of the pocket each coin falls through the same vertical distance, one might properly expect that each coin will have developed the same velocity at the same stage of rotation, based on Galileo's principle that light and heavy objects fall to the earth in the same time, with the same speed. This would be true for the coins if the entire potential energy recovered in the fall were available to accelerate the coins alone. Part of this energy is lost in friction, a substantial part is used up to provide the necessary potential energy to raise the counterweight 17, and another substantial part is used up to provide the necessary kinetic energy in accelerating the drum and its counterweight. These losses constitute a very much larger fraction of the total recovered potential energy of the dime than of the nickel, and therefore at the bottom of the arc of travel, the rotational velocity of the dime is relatively slow, while that of the nickel is relatively very fast.

This higher speed of the nickel delays the release of the coin from step 14b as follows. The relatively strong centrifugal force of the coin presses the coin against the wall of the step, and assisted by friction, it holds the coin there against the gravitational force even when the coin has passed the position at which the slow moving dime drops out readily. As the coin is now moving upward and therefore its velocity is diminishing, and the component of the gravitational force pulling the coin out of the step is increasing, after the coin has passed the partition 21, the coin drops out of the step into the bin 22.

When loaded manually coin by coin, no coin sorting device saves labor, but when the coins are fed to the coin sorter mechanically, the device becomes a labor-saving machine too. So if desired for industrial use, the present device or an appropriate modification thereof may be combined with a mechanical coin feeding device, various forms of which are known in the art. The principles of the invention together with the construction, mode of operation and use of an embodiment thereof most preferred at this time having been explained "in such full, clear, concise, and exact terms as to enable any person skilled in the art to which it pertains . . . to make and use the same," various modifications thereof within the spirit of the invention will occur to those skilled in the art; and I therefore intend to include all such modifications in the appended claim.

I claim:

A scientific educational toy bank for dimes, nickels and quarter dollars, having in cooperative combination

5 a transparent case with a coin slot near the top and a removable base plate, three coin bins in a line arranged inside of said case above said base plate with partitions between each pair of adjacent bins, a coin processing member rotatable around a horizontal axis and positioned inside said case and above said bins, said coin processing member having a coin pocket and being adapted to rotate under the weight of a dime in said pocket, said pocket having a normal loading position pointing generally upward with the upper end thereof open to permit a coin to drop out when in the course of the rotation of said member said pocket is turned generally upside down, means to cause a coin in said pocket to drop out selectively into the bin preassigned for said coin, said means including as a major element a coin diameter discriminative means comprising a shallow recess in said pocket forming a step near the open end of said pocket, said recess being large enough to take a nickel but not a quarter, so that a quarter inserted in said pocket rides on said step and a smaller coin drops into said recess and is held back by said step, thus permitting a quarter to slide out to the bin preassigned for it when said pocket in the course of said rotation slopes downward while a coin in said recess would be checked by said step for later release 10 to a bin preassigned for said coin in said recess, and as another major element a coin weight discriminative means comprising a counterweight associated with said coin processing member and so positioned as to be raised when said coin pocket and the coin therein are traveling downward, and a substantial moment of inertia possessed by said member and said counterweight, said moment of inertia and the weight of said counterweight being adapted to cause sufficiently larger reduction in the rotational speed developed by said rotatable member when loaded with a dime than when loaded with a nickel, to provide sufficient time for a dime to drop into the first available bin when said pocket is generally upside down, and to provide sufficient speed for a nickel to be rotatably carried farther to drop into a farther bin, said counterweight also 15 cooperating with a detent attached to said case to engage a ridge on said member to return said member to a loading position, aligning said open end of said pocket with a coin slot in said case whenever said pocket is empty of a coin.
